UNITED STATES PATENT OFFICE

102,946

DESIGN FOR A BEADED HANDBAG FABRIC

David M. Furman, New York, N. Y., assignor to
Kaplan & Gordon Corp., New York, N. Y., a
corporation of New York

Application December 15, 1936, Serial No. 66,535

Term of patent 3½ years

To all whom it may concern:

Be it known that I, David M. Furman, a citizen of the United States and resident of New York city, (Borough of the Bronx), in the county of Bronx and State of New York, have invented a new, original, and ornamental Design for Beaded Handbag Fabrics, of which the following is a specification, reference being had to the accompanying drawing, forming a part thereof, and in which Fig. 1 is a plan view and Fig. 2 is

an edge view of a piece of beaded handbag fabric showing my new design.

The vertical lining on the substantially rectangular beads represents contrasting primary colors.

I claim:

The ornamental design for a beaded handbag fabric substantially as shown and described.

DAVID M. FURMAN.
